BEACH AND BATHING GARMENT

Margaret R. Cobb, Redondo Beach, Calif.

Application August 19, 1940, Serial No. 353,255

1 Claim. (Cl. 2—67)

It is known that bathing garments made of certain materials, after being wet get out of shape and become unsightly and objectionable. I refer to materials such as crinkly material, crepe, and the like.

I have conceived the idea of making a bathing garment out of two kinds of material or fabric quilted together with an elastic or stretchable stitch, whereby there can be certain elasticity or stretching and return to normal condition.

I accomplish this by using wool-jersey, cotton-jersey, rayon-jersey, or any knitted jersey-like material for the lining of the garment, cut straight with the ribs thereof, and using bias cut material, such as seersucker, crapy fabric and the like, for the outer layer of the garment, and then quilting the two fabrics together with an elastic stitch, either zigzag or chain stitch, or with an elastic thread, quilting in and around such ornamentations as may be on the outer layer of the garment.

By using this method of having a lining cut straight with the ribs or threads thereof, and an outer fabric cut on the bias, or with the threads diagonal to those of the lining layer, and quilted together with a stretchable stitch, the garment will stretch and return to its normal shape, and thus avoid the objection of getting out of shape and becoming unsightly.

In order to more particularly illustrate and describe my invention, I have illustrated the same on the accompanying sheet of drawings, which I will now describe.

Figure 1 is a front view of a form with one of my garments shown thereon;

Figure 2 is a perspective rear view thereof;

Figure 3 is a fragmentary section of two fabrics, with one broken away to illustrate how the two are quilted together; and

Figure 4 is an enlarged inside view of the brassière portion of the garment with parts broken out, showing the inside construction and arrangement.

Referring now in detail to the drawing, the two parts of my improved garment are made with two different fabrics, quilted together in the manner indicated and for the purposes explained.

In the drawing the lining or inner layer may be of any wool-jersey, or cotton-jersey, rayon-jersey or other jersey-like material and is designated in all places as 5, while the outer material, or layer, would be of seersucker, crepe, silk rayon, or other crinkly or crapy fabric, having certain stretching qualities, and cut on the bias, and in

all places in the drawing this outer fabric or material is designated 6.

In the drawing I have shown a two-part garment so made, and have designated the trunks with the reference number 1, indicating the elastic band 8 around the waist, with any kind of fastening means, as zipper fastenings at 9, while the brassière is designated 10, with the upper portions 10', 10' constructed in accordance with my invention, and the lower part 11 of straight construction to resist pull around the body, to be tied in the back, as at 12.

On the inner side of said brassière, as seen in Fig. 4, I have provided two supporting wing-like portions, as 13, 13, to underlie and support the breasts, in a manner understood in the art.

An important feature of my invention is the quilting of the two different layers, or fabrics, together with a stretchable stitch, designated 14 in all places. This can be a zigzag, chain, or other undulating seam, or any stretchable seam, whereby to permit the stretching of the materials and their return to normal form, when dry.

In Fig. 3, it will be noted that the inner fabric, 25 of wool, cotton, or jersey-like material, designated 5, is cut straight with the warp and woof of the material, the lines indicating the straight right angle relationship of the threads of the fabric, while the outer garment or layer 6, is shown 30 cut on the bias, as is indicated by the lines thereon for indicating the warp and woof thereof.

On the drawing I have shown the zigzag or undulating form of seam or stitch, designated 14, and this even on straight pull will permit of 35 certain stretching in all directions, and the return to normal form.

Any decorations can be used, of course, and for this I have simply indicated the circles representing discs of colored material, which can be 40 in the shape of hearts, clover leaves, or any other design desired, and the seams or stitches 14 are shown in and around the same and forming part of the decorations in the form shown.

It will be understood, of course, that many different designs can be used and different forms of 45 stitch or seam can be used, just so long as the seam used permits the stretching intended when the garment gets wet and must be dried, and I do not, therefore, limit my invention to the showing 50 made for descriptive purposes, except as I may be limited by the hereto appended claim.

I claim:

As a new article of manufacture, a beach or bathing garment devoid of rubber fabric but 55 possessing the characteristics of stretch and re-

turn to normal condition, comprising a body adapted to fit and overlie a substantial area of the human form, and means for holding the same in place when in use, said body portion consisting of superposed layers of fabric, the one being an under layer formed in part of threads and cut parallel to the said threads, and an outer layer formed in part of threads and cut on the bias so that its threads run diagonally to those of the

under layer, the layers being relatively free in many areas, crossed lines of stretchable stitching defining said areas and constituting the means for fastening the layers together while permitting stretch of the garment transversely and longitudinally and return of the layers to normal position following such stretch.

MARGARET R. COBB.
